UNITED STATES PATENT OFFICE

2,574,009

KNITTING MACHINE

Alexander Belford and Fred A. Kuss, Laconia, N. H., assignors to Scott & Williams, Incorporated, Laconia, N. H., a corporation of Massachusetts

Application August 20, 1949, Serial No. 111,484

16 Claims. (Cl. 66—153)

1

This invention relates to knitting machines and has particular reference to take-up means involved in the production of stockings in a continuous string in the formation of which various sections are knitted under tension for the purpose of proper stitch formation. In particular, the invention relates to take-up means provided for the knitting of stockings containing inturned welts.

Individual separate stockings may be knit starting with bare needles in accordance with the procedure and utilizing such instrumentalities as are disclosed in the patent to R. W. Scott No. 1,282,958, dated October 29, 1918. In accordance with this procedure, which need not be repeated herein in detail, a non-ravelling selvage is first produced and thereupon loops are transferred to transfer elements which hold the initial courses during the knitting of a hem or welt, there being produced in the formation of this welt a sufficient number of courses to secure the desired length thereof. At the completion of the welt the loops which were held by the transfer elements are returned to the needles and knitting is resumed tying the welt into loops at the beginning of the leg so that a doubled or inturned welt is produced. The welt fold as it is being formed and thereafter has generally been carried away from the needles merely by gravity with only initial assistance by a presser such as shown in said Scott patent. The foregoing method has been quite satisfactory but it is has been recognized that more uniform and perfect stitches might be formed if tension was applied between the stitches being knitted and others previously knitted. Furthermore, more satisfactory results would be obtained if the tension could be applied through a substantial length of the fabric.

In accordance with the present invention suitable means for applying tension to the fabric is provided through the use of take-up rolls which may be caused to stop or to advance at varying speeds as determined by control mechanism, thus to apply a uniform but variable tension to the fabric.

It will be obvious that when knitting is begun on bare needles there can be no satisfactory connection between the initial courses and a take-up located a substantial distance from the point of knitting. In accordance with the present invention the yarn is not taken entirely out of action but rather the regular yarn is changed in order that one or more courses of stitches may be knitted from a yarn having sufficient strength

5 for knitting and providing a connection between successive stockings but frail enough to permit the various finished stockings to be torn apart or separated. Accordingly, it is possible to feed the continuous string of stockings at all times to a take-up remote from the point of knitting. During the time that the welt or hem is being knitted such a remote take-up is incapable of exerting tension on the welt section of the fabric since the last course of fabric under the influence of the take-up will have been removed from the needles and held by the transfer elements. The invention accordingly provides a tube located inside of the needle cylinder and stationary with respect to a revolving cylinder (or rotating with respect to a stationary cylinder), this tube having at the inside of its upper end one or more baffles having camming action on the welt to effect movement of the fabric as it is produced smoothly away from the needles and their cooperating sinkers in such a manner that neither distorted nor unsightly stitches will be produced.

The general objects of the invention will become apparent from the foregoing discussion. These and other objects particularly relating to details of construction and operation, and the accomplishment of these objects, will become more apparent upon consideration of the following description read in conjunction with the accompanying drawings in which:

Fig. 1A is an elevation partially in section of the upper portion of a knitting machine having devices provided in accordance with the invention;

Fig. 1B is an elevation of the lower portion of the same machine, Fig. 1B being, in effect, a lower continuation of Fig. 1A;

Fig. 2 is a fragmentary sectional view showing in detail the construction of the means for taking up the welt; and

Fig. 3 is a plan view of the matter illustrated in Fig. 2 showing in addition a presser of the general type illustrated in said Scott patent.

The figures show only those elements of a rotary cylinder circular knitting machine as are required for an understanding of the invention. It will, of course, be understood that this machine contains conventional elements well known to the art and, in particular, reference may be made to said Scott patent for a more complete showing and description of those elements particularly concerned with welt formation. As will be apparent hereafter various fea-

tures of the invention are applicable to machines of the stationary cylinder-rotary cam type but for clarity and consistency of the description there will hereafter be referred to only a machine of the rotary cylinder type.

The needle cylinder illustrated at 2 is slotted to carry needles 4 with which cooperate conventional sinkers 6. A rotary dial 8 carries transfer elements 10 of the type described in said Scott patent. Relative movements of conventional character are imparted to these various instrumentalities in conventional fashion. A cylinder 12 which does not rotate is provided below the needle cylinder and serves to support it through bearings 14, the cylinder 12 being provided with a bracket 16 arranged to be acted on by a lever 18 having a follower 20 movable by suitable cams on the main cam drum 22 of the machine to effect axial movements of the needle cylinder for the purpose of adjusting the lengths of stitches drawn by the needles by producing relative movement between the needle cylinder and the needle actuating cams.

Located within the needle cylinder is a tube 24 which is held at its lower end in a flange 26 secured by screws 28 in the upper end of the non-rotating cylinder 12. The flange 26 may be axially adjusted with respect to the cylinder 12 and after being secured thereto will partake of the axial movements of both cylinder 12 and needle cylinder 2. The tube 24, by reason of its mounting, does not rotate and the fabric as it is formed passes down through this tube, rotating therein. It will be noted that the upper end 30 of the tube 24 is flared outwardly forming substantially a smooth continuation of the inner surface of the needle cylinder assembly.

At the lower portion of the machine there is provided a take-up assembly indicated generally at 32 and having an upper bearing at 34 and a lower bearing at 36 in the machine frame. The assembly includes a fabric receptacle indicated at 38. A gear 40 carried by the assembly meshes with a pinion 42 on the lower end of an upright shaft 44 which at its upper end carries a pinion 46 meshing with the gear 48 through which the needle cylinder is driven in conventional fashion. The arrangement is such that the take-up assembly rotates in unison with the needle cylinder but since the two are connected through the external shaft 44 it is possible to have the non-rotating cylinder 12 between them as illustrated.

A guide 50 forming part of the assembly 32 mounts a slide 52 which carries at its lower end a cross head 54 on which are pivoted pawls 58 and 60 urged into engagement with ratchet wheels 62 and 64 by a spring 61. A spring 56 urges the slide 52 upwardly. The ratchet wheels 62 and 64 are carried by the shafts of rollers 66 and 68. The rollers are urged together by a spring arrangement indicated at 72. These rollers may be surfaced in various fashions to secure proper take-up of the particular fabric being knit; for example, one of the rollers may be covered with smooth fabric and the other with corduroy, pile fabric or the like, or one of the rollers may be cloth surfaced and the other formed of corrugated wood, or other arrangements may be used, such as the use of a pair of metallic rollers. A detent 70 prevents reverse movement of one of the ratchets this generally sufficing to insure maintenance of tension though, if desired, detents may be associated with both ratchets.

A cam 74 is carried by a lever 76 pivoted to the

frame at 78 and urged by a spring 80 to bring a follower pin 82 into contact with suitable cams such as 84 and 86 on the main cam drum 22. The cam arrangement serves to position the lever 76 and its cam 74 to secure various conditions. If the cam 74 is in its uppermost position the slide 52 will miss it during rotation and consequently will remain in its uppermost position such as defined by the location of the cross head 54 against the top flange of the receptacle 38. Accordingly, no advancing movements would then be given to the rollers 66 and 68 with the result that take-up action would not occur on the fabric. If, however, the cam 74 is lowered to an extent determined by a cam such as 86 on the main cam drum the slide 52 will be depressed upon each rotation causing the pawls 58 and 60 to be moved downwardly to engage beneath new teeth on the ratchet wheels. Then as the slide 52 is released by the cam the spring 56 will move it upwardly causing the pawls to advance the rollers, this advance being of a yielding nature since it is under the action of the spring 56. Desirably the spring 56 is anchored adjustably at its upper end so that the amount of tension may be varied and consequently with it the take-up force applied to the fabric. It will be noted that with this setting of the cam 74 and by using the yielding arrangement provided by the spring 56 an undue amount of tension on the fabric would prevent the upward movement of the slide 52 so that in the next rotation the slide might not be again depressed sufficiently to cause engagement by the pawls of new teeth on the ratchet wheels. The result, therefore, is to provide a take-up exerting at least on the average a substantially uniform pull on the fabric determined by the setting of the spring 56.

Under some circumstances, however, an even greater tension is required and this may be secured by causing the cam 74 to be still further lowered by a cam such as 84 on the main cam drum. Under these conditions the normal movement of the slide is such as to cause the pawls to be moved downwardly to the extent of two new teeth during each rotation. As a result, the spring 56 will be still further tensioned to an average condition corresponding approximately to the increased displacement occurring due to the increased movement of the slide 52.

It will be seen from the above that the tension may be either wholly removed or may be made to exist to varying degrees (even greater than that corresponding to the double tooth movement as described above) depending upon the portions of the stocking which are being knit. During the formation of the welt, for example, since the stitches at the beginning of the welt are being held it is desirable to eliminate the take-up action. The same is generally true at the time stitches are held during the formation of heels and toes during reciprocation, this being particularly desirable in the formation of the heel so as not to stretch the instep loops which are being held and which, if stretched, might produce a noticeable line across the instep of the stocking. Limit of tension may also occur by slippage of the take-up rolls relative to the fabric.

If desired, the take-up rolls may be positively driven by cam action on pawls driving ratchets secured to the rolls. In such case limit of tension will be secured by slippage of the rolls.

Reference may now be made particularly to Figures 2 and 3. In the inside of the upper end

of tube 24 there is secured a fin 88 extending inwardly and provided with an inner smooth rolled edge. This edge of the fin at 90 merges horizontally and smoothly with the upper end of the tube. Its lower end at 92 also merges into the surface of the tube in smooth fashion, this merger preventing catching of the fabric on the fin during reciprocation. A presser 94 which corresponds to the presser P of Scott Patent 1,282,958 and which may be similarly controlled has a position such as illustrated in Figure 3 above the level of the top of the tube. As an indication of the position of the fin 88 there is indicated at 96 the approximate radial location of the center of the sinker cam and at 98 the approximate radial location of the lowest point of the stitch cam. It has been found that the fin operates most effectively if it is set at an angle of approximately 42° with respect to a horizontal plane and extends inwardly about 5% to 1/8 inch from the inner cylindrical wall of the tube 24.

The fin 88 performs its function during the knitting of the welt. The inward movement of the fabric forming the welt is begun by the action of the presser 94 (or equivalently by use of an inwardly directed blast or air) as there are formed the courses immediately following the holding of loops on the transfer elements 19, the presser serving to force inwardly the loop of fabric which is then being produced. At this time the previously formed stocking, with its toe located in the upper end of the needle cylinder, is under tension and if special provisions were not made the fabric loop, after the presser 94 ceased to be effective, would be held against the inside of the tube 24 and would not feed downwardly between the stocking and the tube to make way for the courses newly formed. By reason of the provision of the fin 88, however, a frictional camming action is exerted on this loop of welt fabric tending to urge it downwardly as it rotates counterclockwise relative to the fin and tube and this downward movement takes place despite the pressure of the toe inside the loop of fabric. It has been found that the fin is thoroughly effective in producing this action to cause the welt to feed downwardly thereby clearing the space immediately inside the needles and sinkers.

What is claimed is:

1. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, and a fin carried by the last mentioned cylinder acting to cam inwardly and downwardly fabric constituting a turned welt.

2. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, and a fin carried by the last mentioned cylinder acting to cam inwardly and downwardly fabric constituting a turned welt, said fin having a rounded inner edge sloping in skew relationship with the axis of the cylinders.

3. In a circular knitting machine, a needle cylinder, needles slideable in said cylinder, means

associated with said needles for holding stitches during the formation of a turned welt, a cylinder located inside the needle cylinder, there being relative rotation between the needle cylinder and the last mentioned cylinder, and a fin carried by the last mentioned cylinder acting to cam inwardly and downwardly fabric constituting a turned welt, said fin having a rounded inner edge sloping in skew relationship with the axis of the cylinders, said edge merging with the top edge of the last mentioned cylinder.

4. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, and a fin carried by the last mentioned cylinder acting to cam inwardly and downwardly fabric constituting a turned welt, said fin having a rounded inner edge sloping in skew relationship with the axis of the cylinders, said edge at its lower end merging tangentially with the inner surface of the last mentioned cylinder.

5. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for pulling knitted fabric downwardly through the last mentioned cylinder, and a fin carried by the last mentioned cylinder acting to cam inwardly and downwardly, about fabric of a previously knit stocking, the fabric constituting a turned welt.

6. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for pulling knitted fabric downwardly through the last mentioned cylinder, and a fin carried by the last mentioned cylinder acting to cam inwardly and downwardly, about fabric of a previously knit stocking, the fabric constituting a turned welt, said fin having a rounded inner edge sloping in skew relationship with the axis of the cylinders.

7. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for pulling knitted fabric downwardly through the last mentioned cylinder, and a fin carried by the last mentioned cylinder acting to cam inwardly and downwardly, about fabric of a previously knit stocking, the fabric constituting a turned welt, said fin having a rounded inner edge sloping in skew relationship with the axis of the cylinders, said edge merging with the top edge of the last mentioned cylinder.

8. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for

pulling knitted fabric downwardly through the last mentioned cylinder, and a fin carried by the last mentioned cylinder acting to cam inwardly and downwardly, about fabric of a previously knit stocking, the fabric constituting a turned welt, said fin having a rounded inner edge sloping in skew relationship with the axis of the cylinder, said edge at its lower end merging tangentially with the inner surface of the last mentioned cylinder.

9. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for pulling knitted fabric downwardly through the last mentioned cylinder, a fin carried by the last mentioned cylinder acting to cam inwardly and downwardly, about fabric of a previously knit stocking, the fabric constituting a turned welt, and means controlling the pulling action of said take-up means.

10. In a circular knitting machine, a rotary needle cylinder, needles slideable in said cylinder, means associated with said needles for holding stitches during the formation of a turned welt, a non-rotating cylinder located inside the needle cylinder, take-up means for pulling knitted fabric downwardly through the last mentioned cylinder, shafting geared externally to the needle cylinder and said take-up means to drive the latter rotationally with the needle cylinder, and a fin carried by the last mentioned cylinder acting to cam inwardly and downwardly, about fabric of a previously knit stocking, the fabric constituting a turned welt.

11. In a circular knitting machine, a rotary needle cylinder, needles slideable in said cylinder, means associated with said needles for holding stitches during the formation of a turned welt, a non-rotating cylinder located inside the needle cylinder, take-up means for pulling knitted fabric downwardly through the last mentioned cylinder, shafting geared externally to the needle cylinder and said take-up means to drive the latter rotationally with the needle cylinder, means controlling the pulling action of said take-up means, and a fin carried by the last mentioned cylinder acting to cam inwardly and downwardly, about fabric of a previously knit stocking, the fabric constituting a turned welt.

12. In a circular knitting machine, a rotary needle cylinder, needles slideable in said cylinder, means associated with said needles for holding stitches during the formation of a turned welt, a non-rotating cylinder located inside the needle cylinder, take-up means for pulling knitted fabric downwardly through the last mentioned cylinder, shafting geared externally to the needle cylinder and said take-up means to drive the latter rotationally with the needle cylinder, and

means carried by the last mentioned cylinder acting to draw inwardly and downwardly fabric constituting a turned welt.

13. In a circular knitting machine, a rotary needle cylinder, needles slideable in said cylinder, means associated with said needles for holding stitches during the formation of a turned welt, a non-rotating cylinder located inside the needle cylinder, take-up means for pulling knitted fabric downwardly through the last mentioned cylinder, shafting geared externally to the needle cylinder and said take-up means to drive the latter rotationally with the needle cylinder, means controlling the pulling action of said take-up means, and means carried by the last mentioned cylinder acting to draw inwardly and downwardly fabric constituting a turned welt.

14. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for pulling knitted fabric downwardly through the last mentioned cylinder, means carried by the last mentioned cylinder acting to draw inwardly and downwardly fabric constituting a turned welt, and means controlling the pulling action of said take-up means.

15. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, and means fixedly carried by the last mentioned cylinder engaging the fabric constituting a turned welt to draw it inwardly and downwardly.

16. In a circular knitting machine, a needle cylinder, needles slideable in said cylinder, means associated with said needles for holding stitches during the formation of a turned welt, a cylinder located inside the needle cylinder, there being relative rotation between the needle cylinder and the last mentioned cylinder, take-up means for pulling knitted fabric downwardly through the last mentioned cylinder, and means fixedly carried by the last mentioned cylinder engaging the fabric constituting a turned welt to draw it inwardly and downwardly.
